CLAIM

The ornamental design for a dispenser for paper rolls, as shown and described.

DESCRIPTION

FIG. 1 is a top, front, and left side perspective view of a dispenser for paper rolls showing my new design, the undisclosed rear being plain and unornamented;

FIG. 2 is an enlarged right side elevational view thereof;

FIG. 3 is an enlarged top plan view thereof, the bottom being identical in appearance;

FIG. 4 is a top, front, and left side perspective view of a second embodiment thereof, the undisclosed rear being plain and unornamented;

FIG. 5 is an enlarged right side elevational view of the embodiment of FIG. 4; and,

FIG. 6 is an enlarged top plan view of the embodiment of FIG. 4, the bottom being identical in appearance.

FIG. 4

FIG. 5

FIG. 6
